US00D847752S

(12) **United States Design Patent** (10) Patent No.: **US D847,752 S**
Barrefelt et al. (45) Date of Patent: ** May 7, 2019

(54) **ELECTRICAL OR OPTICAL CONNECTOR**

(71) Applicants: **Tyco Electronics Svenska AB**, Uplands Vasby (SE); **TE Connectivity Nederland B.V.**, AR s-Hertogenbosch (NL)

(72) Inventors: **Rickard Barrefelt**, Stockholm (SE); **Sebastiaan Roger Neerincx**, Tilburg (NL); **Albert Pieter Jan Mooij**, Hedel (NL); **Andreas Winandus Dieduksman**, s'Hertogenbosch (NL); **Alexandra Petronella M. Dermisek-Van De Langenberg**, Dongen (NL)

(73) Assignees: **Tyco Electronics Svenska AB**, Vasby (SE); **TE Connectivity Nederland B.V.**, s-Hertogenbosch (NL)

(**) Term: **15 Years**

(21) Appl. No.: **29/649,320**

(22) Filed: **May 29, 2018**

(57) **CLAIM**

The ornamental design for an electrical or optical connector, as shown and described.

DESCRIPTION

FIG. 1 is a bottom, front, and right side perspective view of an electrical or optical connector;

FIG. 2 is a front view thereof;

FIG. 3 is a rear view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, front, and right side perspective view of a second embodiment of an electrical or optical connector;

FIG. 9 is a front view thereof;

FIG. 10 is a rear view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines shown in the drawings are included for the purpose of illustrating environmental structure and form no part of the claimed design.

1 Claim, 14 Drawing Sheets
